UNITED STATES PATENT OFFICE.

ALFRED S. POWELL, OF NEW YORK, N. Y.

DEVICE FOR ORNAMENTING SHADES OR REFLECTORS.

1,254,729.

Specification of Letters Patent. Patented Jan. 29, 1918.

Application filed November 3, 1917. Serial No. 200,210.

To all whom it may concern:

Be it known that I, ALFRED S. POWELL, a citizen of the United States, residing at New York, in the county of Kings and State 5 of New York, have invented certain new and useful Improvements in Devices for Ornamenting Shades or Reflectors, of which the following is a full, clear, and exact description.

10 In recent years the art of semi-indirect lighting has been greatly extended and is now in wide use. In many places, however, such as residences, the method has made less progress. This is due to several causes.

15 For instance, in residences where the old direct system is already in use the expense of the change militates against the adoption of the newer method, but there are coming on the market various semi-indirect lighting 20 devices of low cost, so that the factor of expense is now less important. However, the inexpensive devices available for the purpose suffer from a lack of ornamental character and are for that reason barred from

25 many homes, offices, halls, and other places where their plainness, not to speak of actual ugliness, would be out of harmony with the other furnishings of the apartment.

The inexpensive devices to which I have 30 referred usually include a flat shade or reflector such as is commonly used with "cluster" lights at the ceiling, and this flat reflector is in most cases the objectionable part of the installation, because it is simply a 35 flaring plate of opal glass, plain and unornamented. I have therefore been led to devise my present invention, which has for its object to provide a ring of sheet metal which can be ornamented as desired, for securing 40 around the edge of the flat shade as a finish thereto. To this end the invention consists in a split sheet metal ring, capable 45 of expansion and contraction to fit shades of various diameters, the ends of the ring 50 overlapping and provided with means by which they are held snugly together in adjusted position so as to conceal the joint as well as may be.

The preferred embodiment of the invention 55 is illustrated in the annexed drawing, in which—

Figure 1 is a perspective view showing the ring in place on a flat shade or reflector.

Fig. 2 is a section on line 2—2, looking in 60 the direction of the arrows.

Referring to the drawing, 10 designates

the flat shade or reflector. The ring 11 is in the form of an annulus which in the present instance is cylindrical in shape. It is made of a strip of spring sheet-metal, preferably 60 brass, or steel plated with brass, bent to circular form with its ends overlapping as shown. At the lower edge the ring or band has a circumferential recess 12 to fit over the edge of the shade 10 so as to hold the 65 band on the shade with all necessary security and thereby prevent tipping of the band.

Means are provided to prevent unintended expansion of the ring, and also to hold the outer end closely against the other, thereby 70 more effectually concealing the joint. For these purposes in the present instance I provide the upper and lower edge-portions of the ring with a series of small hollow rounded projections, as 13, made by pressing the 75 metal outwardly, forming recesses on the inside of the band, so that when the ends are overlapped the projections on the inside end will fit into the recesses on the outside end, as will be readily understood; and I also 80 provide, in the present instance, a keeper 14 in the form of a strap of metal soldered or otherwise attached to the upper and lower edge of the outside end at the extremity thereof. This strap serves to hold the ends 85 against radial expansion and thereby keeps the aforesaid projections and recesses in engagement, which latter effectually prevent circumferential expansion. The result is that the band is held securely in place with 90 the circumferential groove or recess 12 firmly embracing the edge of the shade, but by using a little force the inner end can be pushed or pulled in the keeper, thus contracting or expanding the ring to permit removal or replacement or to fit it to shades of different sizes. In general, a single keeper, carried by the outer end and embracing the inner end, is sufficient for the purpose, since 95 radial displacement of the inner end in the 100 inward direction is effectively prevented by the shade itself.

In the construction shown, in which the recesses and projections 13 are provided, the increase or decrease in size caused by expanding or contracting the ring will be 105 found gradual enough for all practical purposes, especially if the projections are small and close together. In some cases the projections and indentations can be dispensed 110 with, especially when the ring is made of thin metal, and reliance placed wholly upon

the keeper, but in general I prefer to use both.

The ring can be made in a size large enough to fit the larger reflectors, and for smaller reflectors can be contracted by manual adjustment. This would, however, in many cases mean a longer overlap of the ends than is necessary (two or three inches being usually sufficient) and hence would involve a waste of metal. Instead, the ring may be made in several standard sizes, with provision for sufficient expansion to fit intermediate sizes.

The ring can be ornamented as desired, by embossing, etching, enameling, etc., and when in use provides a "finish" which greatly improves the appearance and entirely eliminates the unsightly plainness of the reflector.

It is to be understood that the invention is not limited to the embodiment herein specifically illustrated but can be embodied in other forms without departure from its spirit.

I claim:

1. A device for ornamenting a flat shade or reflector, comprising a contractible and

expansible split ring of sheet metal provided with means for engaging the edge of the shade or reflector the ends of the ring being over-lapped and provided with coöperating means to prevent expansion, whereby the ring can be adjusted to fit the reflector and the joint at the ends of the ring is rendered unnoticeable.

2. A device for ornamenting a flat shade or reflector, comprising a contractible and expansible split ring of resilient sheet metal provided with means for engaging the edge of the reflector, the ends of the ring being overlapped and provided with coöperating projections and recesses and one of the ends having a keeper embracing the other, whereby when the ring is fitted to the reflector displacement of the ring and of its ends in any direction is prevented.

3. A device for ornamenting a flat shade or reflector, comprising the ring described in claim 2, in which the keeper is carried by the extremity of the outer end of the ring and embraces the inner end.

In testimony whereof I hereunto affix my signature.

ALFRED S. POWELL.
